UNITED STATES PATENT OFFICE

JOHANNES KESSLER, OF LONG ISLAND CITY, NEW YORK

BOAT PROPELLING SYSTEM

Application filed August 31, 1932. Serial No. 631,213.

This invention relates to propulsion systems for advancing boats and has as an object to provide a power operated device for producing water suction at one end of the boat 5 and to deliver the water at the other end through tubes secured in the hull of the boat.

A further feature is in the provision of two longitudinally extending tubes, arranged in spaced relation in the hull, below the water 10 line, the tubes being symmetrically arranged in spaced relation and each provided with an independently driven screw propeller, either of which may be actuated separately, in either direction, or driven in unison, as 15 may be desired.

Finally it is a purpose of the invention to produce an efficient system of boat propulsion in which the propellers are housed centrally in the length of the tubes being 20 thus prevented from becoming damaged by contact with objects in the water.

These advantageous objects are attained by the novel construction and arrangement 25 of parts hereinafter described and shown in the accompanying drawing, forming a material part of this disclosure, and in which:—

Figure 1 is a side elevational view of a conventional type of dispatch or pleasure boat, showing an embodiment of the invention as 30 built therein.

Figure 2 is a top plan view of the same.

Figure 3 is a transverse sectional view taken on line 3—3 of Fig. 1, and drawn to an enlarged scale.

The hull 10 of the boat is shown to be of 35 stream line design, provided with a seat 11, hood 12 at the rear of the engine housing 13 and rudder 14.

On each side of the hull 10, at the bow of 40 the boat, and below the water line are intake openings 15 guarded by upright bars 16, constituting a rigid screen to prevent the entrance of fish, marine growths and like floating impedimenta from entering tubes 17.

These inlet tubes are preferably disposed 45 closely against the inner surface of the hull, following its general contour to a point amidship, where they are curved inwardly, as at 18, and then directed in parallel, as at 19.

A continuation of these parallel elements

extend as straight spaced tubes 20 to outlets 21 in the boat sides near the stern, as plainly shown.

Set in the elements 19 are rigid frames 22 to support bearings 23 for shafts 24 to the 55 rear ends of which are fixed screw propellers 25.

The forwardly extending portions of the shafts 24 pass through stuffing boxes 26 on the inner sides of the inlet tubes 18, to the engines 60 27 in the bow of the boat.

These engines are independent of each other, so that one or both may be driven in either direction, or in opposite directions, as 65 in turning, effectively and materially assisting in the operation of the rudder 14.

It is to be noted that the area of the tube elements 17—18, is in excess of the area of the delivery tubes 21, so that a full water supply is obtained.

Due to the symmetry of the arrangement, the small space occupied and the efficiency obtained, the performance is highly advantageous.

Obviously a single central tube might be 75 used in place of the pair shown, or even in combination with them and it is to be noted that no "wash" or ebullition of the water is set up, therefor being particularly valuable 80 in canals.

As changes in the construction could be made within the scope of the invention, it is intended that all matter contained in the foregoing description or shown in the accompanying drawing shall be interpreted as illustrative 85 and not in a limiting sense.

The boat shown in the drawing is for purpose of illustration only, the system is not restricted thereto however, but may be used for 90 all water vehicles.

Having thus described the invention, what is claimed as new and desired to be secured by Letters Patent, is:

1. A boat having tubes extending longitudinally throughout the lengths of its hull 95 in spaced relation and below the water line, a screen at the bow entrance to said tubes, propellers rotatably mounted substantially centrally in the length of said tubes, and independent motors coupled to each propeller, 100

said motors being inset from the forward portions of said tubes.

2. A boat having a pair of tubes extending longitudinally within its hull in close relation thereto in the forward part of the boat, and having parallel extensions of lesser area open at the stern, an engine alined with each extension, shafts from the engines passing through stuffing boxes into the tubes, and propellers 10 fixed on said shafts to cause a forced circulation of water through said tubes.

3. A boat having tubes extending longitudinally within its hull in spaced relation and below the water line in a substantially 15 level plane, said tubes having openings spaced uniformly at their open forward extremities and closely following the hull to a point amidship, thereafter extending in parallel to their open rear ends at the stern, a 20 screen at the entrance of said tubes, engines disposed adjacent the forward portions of tubes to aline with the parallel portions thereof, and propellers intermediate the lengths of said tubes driven by said engines.

25 In witness whereof I have signed my name to this specification.

JOHANNES KESSLER.
